UNITED STATES PATENT OFFICE.

FRANK P. MEIER, OF WILMINGTON, NORTH CAROLINA.

STOVE.

Application filed December 19, 1923. Serial No. 681,563.

To all whom it may concern:

Be it known that I, FRANK P. MEIER, a citizen of the United States, residing at Wilmington, in the county of New Hanover and State of North Carolina, have invented certain new and useful Improvements in Stoves, of which the following is a specification, reference being had to the accompanying drawings.

10 This invention relates to certain improvements in stoves and has relation more particularly to a stove especially designed and adapted for use in connection with fire-places and it is an object of the invention to provide novel and improved means whereby the chimney or draft flue of the fire-place may be closed.

15 It is also an object of the invention to provide a novel and improved draft closure or flue stopper which may be readily adjusted in order to be used in connection with fire-places of various sizes and which draft closure or stopper is separable from the stove proper yet is provided with means for co-action with the stove to constantly urge the draft closure or flue stopper upwardly in firm contact with the walls of the fire-place.

20 It is also an object of the invention to provide in connection with a stove novel and improved means whereby a border frame may be adjustably connected therewith and in a manner to facilitate the proper setting of the stove and also to close or cover the space across the top of the stove and 25 downwardly on each side thereof.

25 The invention consists in the details of construction and in the combination and arrangement of the several parts of my improved stove whereby certain important advantages are attained and the device rendered simpler, less expensive and otherwise more convenient and advantageous for use, as will be hereinafter more fully set forth.

30 The novel features of my invention will 35 hereinafter be definitely claimed.

In order that my invention may be the better understood, I will now proceed to describe the same with reference to the accompanying drawings, wherein:—

40 Figure 1 is a view in elevation illustrating a stove constructed in accordance with an embodiment of my invention and in applied position;

Figure 2 is a horizontal sectional view taken through the upper portion of the 55 structure as illustrated in Figure 1;

Figure 3 is a vertical sectional view taken through the structure illustrated in Figure 1 with the stove proper in elevation;

Figure 4 is a view in plan of the plates 60 comprised in the draft closure or flue stopper, the plates being separated;

Figure 5 is a view in plan of the collar associated with the draft closure or flue 65 stopper;

Figure 6 is a view in perspective of one of the members for holding the border frame in proper position with respect to the stove proper.

70 As disclosed in the accompanying drawings, S denotes a stove adapted to be partly arranged within the fire-place F and which is provided at its top and at the rear with the smoke pipe P for conducting smoke and waste products of combustion up the chimney flue C.

75 As is particularly illustrated in Figures 1 and 2, the stove S seats directly upon the hearth and its rear portion is disposed on a downward and inward incline which is of 80 particular advantage in assuring that the fuel, such as wood or the like within the stove, will be disposed toward the front portion of the stove resulting in a greater efficiency in heat radiation within the room. 85 The lower portion of the stove S preferably at the front, is provided with the draft openings 1 and also with the clean-cut door D. The upper portion of the front wall of the stove together with the adjacent portion of 90 the top of the stove has associated therewith a fuel door A, said door being such to provide, when opened, a materially large opening so that wood or kindred fuel to be burned may be readily applied within the 95 stove.

95 In order to force the heat that radiates from the stove S into the room and keep the air in requisite circulation it is necessary 100 to close or stop the chimney flue C and as herein disclosed, I employ the flue stopper or closure member M. This member M comprises two plates 2 of requisite dimensions to be snugly engaged within the upper portion of the fire-place and which have the adjacent marginal portions in overlying re-

lation, with said marginal portions provided with the recesses or cut out portions 3 which, when the plates are assembled, provide suitable openings through which projects the pipe P. The overlying portions of one of the plates 2 is provided fore and aft with the slots 4 through which extend the bolts 5 carried by the overlying portion of the second plate, said bolts 5 having associated therewith the wing nuts 6 or the like. The bolts 5 and the slots 4 provide means whereby the flue stopper or closure member M may be readily and conveniently adjusted in order to snugly fit within the upper portion 15 of the fire-place while the nuts 6 serve to maintain the plates 2 in desired adjusted position.

Before the flue stopper or member M is applied, a washer W is disposed around the pipe P with its inner margin in close contact therewith, said washer being of such dimensions as to assure a closure of the recesses 3 irrespective of the relative adjustments of the plates 2.

25 As herein disclosed, the washer W is provided with the spring members 7 which contact with the adjacent portion of the stove S whereby the washer W and the applied flue stopper or closure member M are constantly urged upwardly to assure said member M having effective position within the upper portion of the fire-place.

When it is desired to remove the stove S, the member M or washer W may be entirely removed thereby as it is to be noted no portion of the member M is secured or attached to the stove.

In order to regulate the extent of insertion of the stove S within the fire-place F 40 I provide each side of the stove with the plate 8. This plate 8 is provided with a longitudinally disposed slot 9 through which projects a bolt 10 carried by the adjacent side wall of the stove and threaded upon said bolt 10 is a wing nut 11. By this means the plate 8 is held in a desired adjusted position intermediate the forward ends of the stove. The forward end of each of the plates 8 is provided with a pair of 45 outstanding lugs 12 between which are adapted to be engaged the inner marginal

portions of the vertical members 14 of the border frame B.

When the stove S is applied, the frame B is in close contact with the portions of the wall X defining the open front of the fire-place and thereby bridges the spaces at the top and sides of the stove in addition to regulating the position of the stove with respect to the fire-place F. The lower portion 55 of the vertical members 14 of the border frame B are provided with the openings 15 for the admission of cold air while the upper or horizontal portion 16 is provided with the openings 17 for the return to the 60 room of the heated air.

From the foregoing description it is thought to be obvious that a stove constructed in accordance with my invention is particularly well adapted for use by reason of 70 the convenience and facility with which it may be assembled and operated, and it will also be obvious that my invention is susceptible of some change and modification 75 without departing from the principles and spirit thereof and for this reason I do not wish to be understood as limiting myself to the precise arrangement and formation of the several parts herein shown in carrying out my invention in practice except as hereinafter claimed.

I claim:—

1. A fire-place stove having a smoke pipe, a flue stopper for closing the chimney above the stove, said stopper being freely engaged 85 with the smoke pipe and free of connection with the stove, and positive means for urging said flue stopper upwardly of the pipe in contact with the walls of the chimney and the upper wall of the fire-place. 90

2. A fire-place stove having a smoke pipe, a flue stopper for closing the chimney above the stove, said stopper being freely engaged with the smoke pipe and free of connection with the stove, and positive means coacting 95 with the flue stopper and the stove for urging said flue stopper upwardly of the pipe in contact with the walls of the chimney and the upper wall of the fire-place.

In testimony whereof I hereunto affix my signature.

FRANK. P. MEIER.
